John Webster & Joseph E. Holmes, Crawford, Penn.
Sethor's Patent

The Schedule referred to in this Sethor's Patent and making part of the same contains a description in the name of the said John Webster & Joseph E. Holmes, trustees of their improvement in the Trade of Making or Manufacturing paper for writing, printing, wrapping and board from wood.

To all to whom these presents shall come, John Webster & Joseph E. Holmes, of the County of Crawford and State of Pennsylvania, send greeting,

Be it known that the said John Webster and Joseph E. Holmes have invented and doth claim to have a new and useful improvement in Making or Manufacturing paper for writing, printing, wrapping and board from wood, the preparation for which for making the paper is the common paper pulp as follows: to the wood is reduced to shavings of the ordinary factory plane, having size or bunks as to be reduced to nearly the same size of the shavings. They are then placed in a cistern or boiler of sufficient dimensions and covered with water which is put to a strong heat to dry one hundred pounds of the wood that reduced, put from 12 to 18 pounds of alkali either vegetable or mineral in proportion to its quantity for strength of salt brine, and they should be reduced before they are placed on the wood in the cistern or boiler with the water they may have to put in with the water and wood upon reduction has the salt brine so that the heat preferable should come to wood there must be sufficient quantity in all cases to cover water provided, after such water for covering the hundred pounds of wood which may be broken upon being placed in the cistern with the wood & water or alkali in the above stated one hundred pounds of wood that

proposed will be well adapted to make from 5 to 7 pounds of
paper.

In testifying that the above is the specification of the
said improvement as before described, we have herinafter set
down, & seal this 6 May, 1870, A.D. 1870.

Witness,

Sam'l. French

Thos. Stinson

Sam'l. M. Miller

Joseph C. Holmes
